LIGHTING FIXTURE

Gerard Edmund Mulvey, 36 Castle Frank Road, and
George Elliott Boake, 6 Maple Ave., both of To-
ronto, Ontario, Canada

Filed Jan. 16, 1968, Ser. No. 10,186

Term of patent 14 years

Int. Cl. D26—02

U.S. Cl. D48—23

FIG 1

FIG 2

FIG 3

FIGURE 1 is a lower perspective illustration of a light-
ing fixture embodying the said design;

FIGURE 2 is a sectional elevation along the line 2—2
of FIGURE 3; and

FIGURE 3 is a bottom plan view of the lighting fixture
shown in FIGURE 1.

The dominant features of our design reside in the por-
tions shown in full lines.

What we claim is:

The ornamental design for a lighting fixture, as shown
and described.
